UNITED STATES PATENT OFFICE.

AUGIE L. HANSEN, OF EVANSTON, ILLINOIS, ASSIGNOR TO JUSTRITE MANUFACTURING COMPANY, OF CHICAGO, ILLINOIS, A CORPORATION OF ILLINOIS.

ACETYLENE-LAMP.

1,368,143.

Specification of Letters Patent.

Patented Feb. 8, 1921.

Application filed June 27, 1919. Serial No. 307,190.

To all whom it may concern:

Be it known that I, AUGIE L. HANSEN, a citizen of the United States, and a resident of Evanston, in the county of Cook and State of Illinois, have invented certain new and useful Improvements in Acetylene Lamps, of which the following is a specification.

My invention relates to acetylene lamps and particularly to miners' acetylene cap lamps. The invention concerns particularly improved closure mechanism for the water inlet opening of the water container of the lamp.

These lamps are of well known construction. They usually comprise a water container, a carbide container, a valve for controlling the feed of water from the water container to the carbide container, a burner tip connected to receive the generated gas from the carbide container, and a reflector surrounding the tip. Provision is also made for permitting the flow of gas into the water container should the pressure in the carbide container become excessive, and a vent is provided for releasing the gas from the water container. This vent is usually provided in the plug which closes the water inlet opening of the water container. The vent passageway must be kept clear for the free flow of gas therethrough but at the same time, provision must be made for preventing the escape of water with the gas or the escape of water through the filler opening past the plug. Heretofore, the closure plugs have been formed of sheet metal with a vent passageway therethrough and baffle means for preventing escape of water through the passageway. Difficulty has been experienced to construct the metallic plugs sufficiently accurately so that they will at all times accurately seat in the filler opening and entirely seal said opening against the direct outflow of water.

The important object of my invention is, therefore, to produce a closure plug which will accurately and securely fit in the filler opening and through which gas can readily escape and water flow be baffled. In accordance with my invention, I make the side walls of the plug of yielding elastic material

such as rubber which will intimately fill the filler opening and seal it and which will have frictional engagement with the filler opening sides so that the plug is held in the opening against accidental displacement. 55

The construction of my improved closure plug is clearly shown on the accompanying drawing in which—

Figure 1 is a side elevational view of a 60 miner's cap lamp,

Fig. 2 is a plan view of the end of the water container and the closure plug,

Fig. 3 is an enlarged sectional view on plane 3—3, Fig. 2, 65

Fig. 4 is an enlarged side elevational view of the closure plug,

Fig. 5 is a sectional view on plane 5—5, Fig. 4, and

Fig. 6 is a view of the under side of said 70 closure plug.

The lamp shown comprises the water container 10, the carbide cup 11, the valve mechanism 12 for controlling the feed of water from the water container to the carbide cup, 75 the gas conducting tube 13 and the tip 14, and the reflector 15 surrounding the tip. The valve stem 12 is turned by means of the lever 16, and the lamp is supported on the miner's cap by means of a clamp 17 and a hook 18. 80

The water container has in its top wall the water inlet opening 19 which is surrounded by the flange 20. As the lamp is carried on the miner's cap while he is at work, it is violently agitated and the water in the water container thrown about with considerable force. The filler opening must therefore be kept tightly closed during use of the lamp to prevent the escape of the water. At the same time, vent passageway must be provided for the escape of gases which accumulate in the water container when the pressure in the carbide cup becomes excessive. 85 90 95

My improved closure plug P efficiently seals the filler opening and permits unobstructed flow of the gases from the water container. The structure shown comprises the sheet metal top 21 from which extends 100 the tubular shank 22 which at its lower end receives the washer or bottom plate 23. The

shank receives the elastic material 24 such as rubber, this material being held between the top 21 and the washer 23, the lower end of the shank being riveted against the plate as indicated at 25. The material 24 is of a shape to fit within the flange 20 surrounding the filler opening 19. The opening shown is elliptical and the contour of the material 24 is therefore similarly elliptical in order that 5 a snug fit is assured. The top 21 and the washer 23 are also elliptical and the top has the side flanges 26 and 27 which extend downwardly a distance alongside of the material 24 to assist in holding said material in 10 place. The bottom plate or washer may also have upward projections 28 for engaging in the plug material 24 to assist in holding such material on the shank against rotation thereon. In order to prevent loss of the closure 15 plug, it is preferably hinged to the water container. As shown, the top 21 has the tail extension 29 which loops around a supporting staple 30, whose ends extend through the top wall of the water container 20 and are soldered thereto.

The front end of the top 21 is extended and curled over to form a finger receiving projection 31 by means of which the plug structure can be readily swung upwardly to 25 be removed from the filler opening. The sides of the plug material 24, preferably taper so that when the plug is inserted and pressure applied thereto, it will accurately and snugly fill out the filler opening so as 30 to form a perfect seal.

In the construction shown, the shank member 22 is in the form of a tubular rivet whose head *h* has the vent opening 32 therethrough. This vent opening is provided for the out- 35 flow of gas which enters the water container whenever the pressure in the carbide cup becomes excessive. The vent passageway being at the upper end of the shank member, water cannot directly escape therethrough 40 from the water container under ordinary circumstances. However, as before stated, the lamp is violently agitated during its use in the mine, and the gas pressure frequently becomes excessive in the carbide cup and 45 great volumes thereof flow suddenly into the water container and escape under considerable pressure through the vent passageway, the rapidly flowing gas tending to carry water particles with it through the vent passageway. The gas flowing rapidly through 50 the water will also cause considerable splashing thereof. I therefore provide guards or baffle walls at the lower end of the shank member to prevent the splashing of water 55 into the shank member and to receive the water particles dropped by the outflowing gas and return the water to the container. 60 The baffle walls 33 and 34 are part of the bottom plate 23 and extend toward each 65 other from the outsides of the bottom plate

and have a slight downward inclination as clearly shown in Fig. 5, the opposed edges being separated only by a narrow gap 35. The baffle walls are wider than the hollow shank member so that the gas must deflect 70 around the edges of the baffle walls before it can enter the shank member. The edges will remove considerable part of the moisture particles carried with the gas, and before the gas leaves the passageway 32, nearly all of 75 its remaining moisture content will have been dropped or deposited against the walls of the shank, the moisture being then received by the inclined baffle plates and conducted back to the water container. 80

Any water splashing upwardly, will strike the inclined baffle plates and be prevented from reaching the outlet vent. Thus, moisture is at all times prevented from escaping through the vent but the gas is free to flow 85 therethrough. As the elastic plug fits snugly in the filler opening 19, it is impossible for any water to escape through such opening. After a period of use, the water in the water container usually becomes quite 90 hot and if any particles could splash to the exterior, wearing of the lamp would, of course, be quite disagreeable. However, my improved construction prevents any such escape of moisture and the lamp can therefore be worn with confidence and comfort. 95 The rubber plug body engages the filler opening flange with sufficient friction to prevent accidental opening of the plug during use of the lamp. 100

Having thus described my invention, I claim the following:

1. A closure plug structure for the filler opening of the water container of an acetylene lamp, comprising a sheet metal top, a hollow shank extending therefrom, a plug body of resilient material surrounding said shank, a bottom of sheet metal secured to the shank end and serving to hold said body on said shank, the top of said shank having a vent opening therethrough, and baffle walls forming an integral part of the bottom and extending diagonally toward each other into position below the end of said shank. 110

2. A closure plug structure for the filler opening of the water container of an acetylene lamp, comprising a sheet metal top plate, a hollow shank extending therefrom, a plug body of resilient material surrounding said shank, a bottom plate secured to the shank end to hold the plug body to the shank and against the top plate, side flanges on the top plate engaging with the plug body to prevent rotation thereof on the shank, the shank at its upper end having a restricted vent outlet, baffle walls forming an integral part of said bottom plate extending below said shank to prevent the entrance of water thereto. 120

3. A closure plug structure for the filler 125

opening of the water container of a carbid lamp, comprising an elliptical sheet metal top plate, a tubular shank extending from said plate, an elliptical plug body of resilient material surrounding said shank, means for holding said body on said shank, and flanges extending downwardly from said cap and

engaging against the sides of said plug body for preventing rotation of said body on said shank. 10

In witness whereof, I hereunto subscribe my name this 25th day of June A. D., 1919.

AUGIE L. HANSEN.
